[57] CLAIM

The ornamental design for a "safety containment housing for the storage of hazardous waste material", as shown and described.

DESCRIPTION

FIG. 1 is a perspective view of a "safety containment housing for the storage of hazardous waste material", showing my new design;

FIG. 2 is a front elevational view thereof;

FIG. 3 is a right side elevational view thereof, the left side being a mirror image;

FIG. 4 is a rear elevational view thereof;

FIG. 5 is a top view thereof;

FIG. 6 is a bottom view thereof;

FIG. 7 is a cross-sectional view taken in the direction of the arrows of FIG. 2; and,

FIG. 8 is a cross-sectional view taken in the direction of the arrows in FIG. 3.

The broken line showing of the handles is for illustrative purposes only and forms no part of the claimed design.
